UNITED STATES PATENT OFFICE.

ROBERT J. HARRINGTON, OF DALTON, MASSACHUSETTS.

TWIST-EQUALIZER ATTACHMENT FOR SPINNING MULES.

Application filed August 8, 1922. Serial No. 580,574.

This invention relates to improvements in attachments for spinning mules and its leading object is to provide means for regulating the number of turns per inch in the 5 yarn so that the yarn wound on the upper end of any bobbin will have the same number of turns per inch as the yarn on the rest of the bobbin.

This application involves certain improvements over those disclosed in my Patent #875,655, issued December 31st, 1907, and embodies means whereby the mechanism covered by this patent may be utilized for its own purposes and also to carry out those 15 of the present invention.

With the above and other objects in view the invention consists in certain new and useful combinations, constructions and arrangements of parts, clearly described in the 20 following specification and fully illustrated in the accompanying drawings, in which:—

Fig. 1 is a perspective view showing the combined yarn evener and twist equalizer.

Fig. 1^a is a detail of certain parts shown in Fig. 1.

Fig. 2 is an end elevation of a mule head equipped with my improvement.

Fig. 3 is a detail view, partly in section, taken on an enlarged scale, showing the 30 roving gear and the plate for varying the arc of moving of this gear.

Fig. 4 is a detail transverse sectional view taken through the associated operating rod.

Fig. 5 is a detail view of a modified plate 35 construction.

In the manufacture of mule spun yarn there is a tendency of the yarn as it is wound upon the upper ends of the bobbins to slip off the bobbins, thereby varying the turns 40 of twist per inch of yarn from the point when slippage commences until bobbin set is full or ready to be doffed. It is very desirable that the number of turns per inch 45 of yarn length be uniform throughout the bobbin. In the Davis and Furber spinning mules the twists per inch are regulated by means of the well known twist gear and worm arranged to be shifted into and out of driving engagement therewith. The 50 present invention is designed to provide means whereby the number of turns placed in the yarn will be equalized.

As previously indicated certain mechanism disclosed in my Patent 875,655, issued

December 31st, 1907, is utilized, and this will 55 be described.

The frame of the spinning mule is indicated at 5. On this frame the worm driven gear 6 is mounted on mechanism not shown to have a vertical movement with its shaft 7, so as to engage and disengage the worm 8, which is mounted in the bearings 9 on the frame 5. This gear 6 is provided with a series of radially spaced holes 6^a in any one of which one of the pins 10 may be 65 inserted. These pins are retained in their inserted holes by means of the plate 11, which is retained on the shaft 7 of the gear 6 by means of the cotter pin 12. Two pins 10 are located in adjacent holes and between these pins a lug 11^a carried by or formed on the plate 11 projects.

The plate 11 is formed or provided with an external lug 11^b which is engaged by the arm 13 of the lever 14, which is mounted 75 to rotate on the shaft 7, being retained in place by the cotter pin 12. This lever 14 is pivotally connected to the sleeve 15 by means of the set screw 15. The sleeve 15 is mounted on the operating rod 17, which is 80 equipped with a sleeve or collar 18 adjustable thereon by means of the set screw 19, and providing a stop for the sleeve or collar 18.

The upper end of the operating rod 17 85 is pivotally connected with a bell crank lever 20, through the pin shaft 21, which is adjustably secured in the slot 22' of the arm 22. The lever 20 is pivoted at 23 to the bearing 24 of the block 25, which is secured 90 in place by the usual bolt cover 26. The other arm 27 of the lever 20 is provided with a slot 27' to which the block 28 is pivotally and adjustably connected by means of the pin shaft 29 or set screw. The upper end of the rod 17 is held in place on the shaft 21 by means of the cotter pin 21'.

A horizontal shaft 22 is connected at its inner end to the block 28, and is pivotally connected at its outer end by means of the pin shaft 29 to the arm 30 which is secured to the horizontal operating shaft 31 by means of the set screw 32. (Referred to as the rock shaft 58 in my Patent #875,655). The rock shaft 31 is supported upon the 100 spool stand shaft of the spinning mule mechanism, by means of the brackets 33 and 34, which are positively clamped to the 105

spool stand shaft by the screws 35. Each bracket has an upstanding arm 36 which is provided with a longitudinal slot 36'. Each arm 36 is engaged by a pendant arm 37, extending from a collar 38, which provides a bearing for the rock shaft 31. One of the collars 38 is engaged by a stop collar 39 secured against slippage on the rock shaft 31 by means of the set screw 39'. The collar 40 of the other arm is engaged by the collar 40 which carries an arm 41, having a longitudinal slot 41' therein. The collar 40 is held in place by means of the set screw 40'.

The arm 41 is engaged by the arm 42 of the member 43, which carries the bearing block 43, through the connecting set screw 44. The arm 42 is pivotally connected to the arm 41 by means of the set screw 42'.

A horizontal rod 45 extends through the bearing block 43 and to one end of this rod the roving lock slide 46 is pivotally connected by means of the set screw 47. This slide is provided with a slot 46' through which the retaining screw 46'' extends, and which slide is referred to in my Patent 875,655 by the reference 37.

The rock shaft 31 carries a collar 48, which is secured in place by means of the set screw 48'. This collar is provided with an arm 49 which is pivotally connected to the block 50 mounted on the vertical operating rod 51 by means of the set screw 50'.

The lower end of the operating rod 51 is pivotally connected to the slotted arm 52 of the bell crank lever 53 by means of the pin shaft 54, and this bell crank lever is pivoted by the screw 55 to the bearing 56 carried by the bracket 56^a, which is bolted to the mule breast 57. The other arm 58 of the lever is pivotally connected with the horizontal rod 59, which carries the collar 60. This collar is retained in selected position by means of the set screw 61 and is provided with a lateral lug 62 which bears against the end of the back shoe 63, which is referred to by the reference 43 of my previous patent. The rod 59 also carries a collar 64 which is secured thereto by the set screw 65 and this collar engages the bracket 66, which is bolted in position on the bed plate of the mule, the rod 59 extending through a hole in the bracket 66. A third collar 67 is mounted on the rod 59 by means of the set screw 68 and a coil spring 69 is connected at one end to the lug 67^a of the collar 67 and to the bracket 66, so as to maintain tension on the back shoe, through the rod 59, and also on the vertical rod 51 and the parts connected therewith, and previously described.

The roving slide lock engages the roving gear 70, in the manner described in my Patent #875,655, so that the arc of movement of the roving gear will be varied to prevent a thickening of the yarn during the final

phase of the building or winding of the bobbin, by the action of the building shoe, which is actuated by mechanism not shown and which belongs to the well known Davis and Furber spinning mules.

As the building shoe moves against the lug 62 and movement is thus imparted to the roving lock slide the vertical operating rod 17 will be shifted to impart a rotative movement to the lever 14, so that the twist gear 6 will be moved a distance corresponding to the movement imparted to the rod 17 by the building shoe, which action will shorten the arc of movement of the twist gear, thus equalizing the turns or twist of the yarn during the terminal stage of the building of the bobbins, while at the same time the quantity of the yarn is being controlled by the action of the roving lock slide on the roving gear.

The twist equalizer may be used without the yarn evener, and the two may be used, as indicated, together or jointly.

The plate 11 may be formed with an integral arm 11^a and the vertical rod 17 provided with a collar 17^a adapted to abut against this arm to swing the lever 11^a and its plate 11, to vary the relation of the twist gear 6, as in the previously described construction, the inner face of the plate being formed with an integral lug to engage the pins provided on the gear 6.

Having described my invention I claim:

1. The combination with a spinning mule head having a twist controlling gear and equipped with means for shifting said gear into and out of driving engagement with driving mechanism carried by the mule head, of means for regulating the arc of movement of the gear consisting of a member disposed against the side of the gear and provided with a projection adapted to be connected for driving action with the gear and means arranged to be operated by the building shoe of the mule head for shifting said member.

2. The combination with a spinning mule head having a twist regulating gear, of a member mounted against the side of the gear, means for varying the relation of the member to the gear, and means for operating the member to vary the arc of movement of the gear during the period of engagement of the gear with its driving mechanism.

3. The combination with a spinning mule having a twist regulating gear, said gear having a series of radially spaced holes, a plate disposed against the side of the gear and provided with a lug projecting toward the side of the gear, pins insertable in the gear holes, means for driving the gear, means for moving the gear into and out of driving engagement with said driving means, a building shoe and means operated

by the building shoe for causing the plate to shift the gear to vary its arc of movement.

4. The combination with a spinning mule of a twist equalizer, a building shoe, and means controlled by the building shoe for operating the equalizer to maintain the same proportional number of turns per inch in the yarn during the final period of the building of the bobbins as produced during the previous period.

5. The combination with a spinning mule having a twist regulating gear, a building shoe, and means controlled by the building shoe for varying the arc of movement of the twist gear.

6. The combination with a spinning mule

having a twist gear and a roving gear, a building shoe, and means controlled by the building shoe for varying the arc of movement of the twist gear and the roving gear. 20

7. The combination with a spinning mule having a twist gear, said gear having a series of circumferentially spaced openings, a plate disposed against said gear and having a lug facing said gear, pins adjustable in the openings and engageable by the lug, a building shoe, and means controlled by the building shoe for shifting the plate to vary the arc of movement of the twist gear. 25

Signed by me at Dalton, Mass.

ROBERT J. HARRINGTON.
